UNITED STATES PATENT OFFICE.

EDMUND C. MORGAN, OF MORGAN PARK, ILLINOIS

MINING-MACHINE.

1,212,382.

Specification of Letters Patent. Patented Jan. 16, 1917.

Application filed November 8, 1910. Serial No. 590,445.

To all whom it may concern:

Be it known that I, EDMUND C. MORGAN, a citizen of the United States, residing at Morgan Park, in the county of Cook and State of Illinois, have invented certain new and useful Improvements in Mining-Machines, of which the following is a specification.

This invention relates to mining machines particularly adapted, though not necessarily limited in its use, for what is known as "long wall" work, and one of the objects of the invention is to provide an endless cutting apparatus for cutting the coal and which cutting apparatus also forms a conveyer for conveying away the detached pieces of coal to be discharged from the machine at a convenient point.

A further object is to provide an improved mining machine of this character in which there is employed an endless cutting apparatus embodying detachable bits or tools and which apparatus encompasses the driving mechanism so that the bits or tools may be readily removed and replaced from the rear of the machine, thereby permitting the construction of a compact machine of this character.

A further object is to provide an improved machine of this character which will protrude very little outside of the path of the cutting, so that the tracks for the cars will be arranged in close proximity to the face of the coal and inside of the props and so that the tracks may be readily moved over toward the face or wall of the coal as the cutting or mining progresses.

A further object is to provide improved means for supporting and guiding the cutter chains from the lower or under side thereof thereby leaving the upper side free to form a conveyer for the mined or detached pieces of coal.

A further object is to provide an improved endless cutter comprising pivotally connected links and cutting tools secured thereto, the cutting edge of which tools is arranged substantially on a line with the joint or pivot of the cutting links in the rear of the tool, thereby overcoming the tendency of the tools to gouge.

A further object is to provide an improved machine of this character which will be simple, durable and cheap in construction and effective and efficient in operation.

To the attainment of these ends and the

accomplishment of other new and useful objects as will appear, the invention consists in the features of novelty in the construction, combination and arrangement of the several matters hereinafter more fully described and claimed and shown in the accompanying drawings illustrating an embodiment of the invention, and in which-

Figure 1 is a top plan view of an improved machine of this character constructed in accordance with the principles of this invention. Fig. 2 is a side elevation of the machine shown in Fig. 1. Fig. 3 is a detail sectional view taken on line 3-3, Fig. 1. Fig. 4 is a sectional view taken on line 4-4, Fig. 1. Fig. 5 is a detail view partly in elevation and partly in section of a reciprocating tool for breaking down pieces of coal. Fig. 6 is a detail sectional view on line 6-6, Fig. 2. Fig. 7 is a detail plan view of a portion of the cutter chain or belt and one of the cutting tools secured in position thereto. Fig. 8 is a detail sectional view as taken on line 8-8, Fig. 7, showing in dotted lines the relative positions of the cutting tools as they cut the under kerf in the wall of the mine. Fig. 9 is a detail sectional view on line 9-9, Fig. 7. Fig. 10 is a detail sectional view on line 10-10, Fig. 7.

Referring more particularly to the drawings and in the present exemplification of the invention, the numeral 10 designates the main supporting frame, the base of which is adapted to slide along the floor of a drift or gallery, and mounted upon the frame 10 is a motor 11 by means of which the machine may be advanced. This motor 11 is provided with a shaft 12 mounted in suitable journals and a gear 13 is secured to the shaft which meshes with a companion gear 14 on an upright shaft 15, which latter is rotatably mounted in suitable journals. A worm wheel 16 is secured to the shaft 15 for rotation therewith and this worm wheel in turn meshes with a worm gear 17. The worm gear 17 is secured to a shaft 18 for rotation therewith, (see particularly Figs. 1 and 4) and the shaft is journaled in suitable bearings 19. Mounted upon the main frame 10 is a support 20 which is preferably elevated some distance above the base of the main frame and is provided in each of its outer faces with a groove 21, in which grooves are mounted slides 22, one of the slides being mounted on each side of the support. Anchor arms 23 are pivotally con-

nected by one extremity to one of the slides 22 on one side of the support 20 and similar anchor arms 24 are pivotally connected by one extremity to the other of the slides 22 and one pair of these anchor arms is preferably arranged in advance of the other. The arms are of such a length that their free extremities will engage the roof and the floor of the drift or gallery and are of a combined length slightly greater than the height of the drift or gallery. Each of the arms 23 is provided with a projecting ear or lug 25 which latter are connected by means of a bolt 26 passing loosely there-through and an elastic member 27 such as a coil spring or the like, is arranged between the ears or lugs 25 and tend normally to separate the latter so as to force the respective extremities of the anchor arms 23 into engagement with the floor and roof of the drift or gallery. A similar connection is provided between the arms 24. These pairs of anchor arms are arranged at the rear of the machine and are adapted to advance the machine and for this purpose the slides 22 are each connected with a crank arm 28 on the shaft 18, as shown more clearly in Figs. 1 and 4, so that when the shaft 18 is rotated in the manner already set forth the crank arms 28 will alternately move the slides 22 in their guideways 21 in the support 20 in opposite directions. When the slides are moved in their guides in a direction away from the machine, the point of pivotal connection of the respective pairs of arms will be forced in a direction to cause the arms to grip the floor and roof of the drift or gallery, and when in this position, a further movement of the slide in the same direction will force the machine forwardly. When the slides 22 are moved in the guides in a direction toward the machine, the respective pairs of anchor arms will be advanced with respect to the machine so as to secure a new grip on the floor and wall. By alternately advancing the pairs of arms in this manner it will be apparent that when one pair of arms is being advanced, the other pair will act to advance the machine. Supported by the base of the machine and rotatably mounted on upright axes 29, 30, at the forward end of the machine are sprockets 31, 32, which are preferably arranged in line with each other. An idle pulley 33 is rotatably mounted upon an upright axis 34 at the rear of the machine and preferably in line with the axis 30. An upright shaft 35 is also arranged at the rear of the machine and in line with the axis 34 of the pulley 33, and a sprocket 36 is secured to the shaft 35 for rotation therewith.

A cutter comprising an endless belt 37, preferably in the form of a chain constructed of links, which links are pivotally connected, is provided and this endless flexible

member surrounds the sprockets 31, 32, 36 and the idler 33. The cutting tools 38 are removably secured to the endless member 37 in any suitable manner but preferably the endless member is provided with sockets 39, 70 which project beyond the outer side of the endless member and into which sockets one extremity of the tools or cutters project, and the latter are held in position and against accidental displacement in any suitable 75 manner, preferably by means of fastening screws or bolts 40. The endless member 37 encompasses the motor 11 and the operating gears and mechanisms of the cutter as well as the operating mechanism of the remaining portion of the machine so that the cutters or tools 38 may be readily removed from the rear of the machine, thereby enabling the machine to be constructed compactly so that it will operate in the very contracted 85 space in which it is intended to work.

The cutters or tools 38 are arranged at different inclinations so that their cutting edges when in engagement with the wall or the coal to be cut will operate in different 90 horizontal planes, as shown more clearly in Fig. 8, and the cutting edges of the tools are arranged substantially on a line with the joint just in the rear of the tool, and which joint forms the point of pivotal connection 95 of the links of the cutting belt, so that all tendency of the edge of the tool or cutter to gouge the work will be obviated.

The portion of the base of the main frame 10 which extends under the portion of the 100 chain or belt 37 extending across the front of the machine forms a guide 40 shown more clearly in Figs. 7 and 8 and supports the endless member from its lower face. The remaining portion of the endless member 37 105 rests upon the upper face of the base of the main supporting frame 10, so that the endless member is supported entirely from its lower face while the upper face is exposed and is free to engage the detached pieces of 110 coal to form a conveyer for the coal for carrying it to any desired point at which it is to be discharged from the machine, in a manner to be hereinafter set forth. The sprocket 36 and the idler 33 are preferably 115 elevated with respect to the sprockets 31, 32, so that when the pieces of coal are being conveyed by the endless member 37 they will be slightly elevated.

In order to facilitate the conveying of the 120 pieces of coal by the endless member 37 as they fall upon the base 10 of the machine, the upper face of which latter acts as a platform, the endless member 37 is provided with a plurality of laterally projecting fingers or extensions 41 which are preferably arranged adjacent the sockets 39 of the tools and extend from the side of the endless conveyer opposite to the side on which the tools 38 are arranged, and these fingers or 130

projections 41 project over and preferably rest upon the face of the base 10.

Motion is imparted to the endless member 37, and to advance the cutters 38, from the motor 11, and this may be accomplished in any desired or suitable manner but preferably by means of an endless flexible member 42 preferably in the form of a chain or belt, which passes over the sprocket 43 on the shaft 15 and a sprocket 44 on the shaft 35 to which the sprocket 36 is secured (see particularly Figs. 1 and 3). These sprockets 43, 44, are arranged at an elevation above the endless member 37, as shown more clearly in Figs. 2, 3 and 4, and secured to and projecting from the endless member 42 are arms or fingers 45, any number of which may be provided, and these arms or fingers 45 are adapted to engage the detached pieces 46 of the coal as it is brought into proximity to the arms to move the pieces of coal off of the platform formed by the upper face of the base of the machine, the pieces of coal being fed into positions to be engaged by these arms or fingers 45 by the endless member 37 of the cutters.

In order to tighten the endless member 37, the axle 34 of the idler 33 is mounted on an adjustable bearing 47 (see particularly Fig. 1), which latter is adjustably held in position with respect to the base of the machine by a belt and slot connection 48, 49. An adjusting screw 50 is provided which passes through a fixed support 51 and has engagement with the end of the bearing 47 so that by adjusting the screw 50 the bearing 47 and the idler 33 will be correspondingly adjusted.

As the cut pieces 46 of the coal are ejected by the endless conveyer 37, they may be conveyed to the cars 52, which run upon the tracks 53 arranged in close proximity to the face 54 of the wall of the coal by a suitable conveyer which receives the coal when it is thus ejected. This conveyer preferably comprises an endless chain or belt 55 mounted upon an upwardly inclined support 56 and runs over sprockets 57, 58 (see particularly Fig. 3) and one of the sprockets, the sprocket 58, is secured to the shaft 35 on which the sprocket 36 is secured, and the upwardly inclined support 56 is adapted for pivotal movement with respect to the main supporting frame by means of a pivot connection 59. The endless conveyer 55 is provided with laterally projecting arms or flights 60 and an upright wall or partition 61 is provided on the support 56, which operates with the arms or fingers 60 to prevent the pieces of coal 62 being conveyed by the conveyer 55, from falling away from the side of the support adjacent the cars 52 and also serves as a means whereby the pieces of coal will be directed into the cars. The endless conveyer 55 is preferably

arranged below the rear portion of the endless member 37 so that the pieces of coal 46 when ejected from the platform formed by the face of the base of the machine, will fall into position on the support 56 to be conveyed away by the conveyer 55.

The cutters 38 are adapted to cut an under kerf 63 in the wall adjacent the front of the machine and as the machine is advanced, the forward end thereof will be projected into this kerf so that the pieces of coal which are broken down by the reciprocating tool or pick to be hereinafter described, will fall into a position to be conveyed by the endless member 37.

An upright cutter preferably in the form of an endless chain or belt 64 is provided with cutting tools 65 for cutting an upright kerf 66 (shown more clearly in Fig. 1). This endless member 64 passes over sprockets 67, 68, arranged at the front of the machine, and to one side thereof, and which sprockets rotate about horizontal axes 69, 70. A sprocket 71 is also provided in rear of the sprockets 67, 68, over which the endless member 64 passes and this sprocket 71 is preferably arranged in a horizontal plane between the horizontal planes of the shafts 69 and 70 of the sprockets 67, 68, and rotates about a horizontal axis 72. The cutting tools 65 are removably secured to the endless member 64 by being inserted into sockets 73 on the member 64 and are held against displacement by fastening bolts 74. The sprockets 67, 68, are spaced from each other to any desired extent but are preferably arranged so that the foremost run of the endless member 64 will travel in a plane above the plane of travel of the cutters 38 and also so that the upright run at the front of the machine will be so arranged that the cutters carried thereby will travel in an upright plane substantially in line with the upright plane of the cutting edges of the cutters 38 as they travel across the front of the machine. The sprockets 67, 68, are also preferably spaced from each other a sufficient distance so that some of the cutters 65 will extend to the roof of the drift or gallery. Motion is imparted to the upright cutters 65 from the sprocket 71, the shaft 72 of which latter receives its motion from the motor 11 through the medium of a gear 75 on the shaft 15, which gear meshes with a gear 76 on the shaft 72.

The tension of the endless member 64 may be varied in any suitable manner and for this purpose the sprocket 67 is preferably supported by a member 77 (see Figs. 2 and 6) which is pivotally connected to the support 78 of the sprocket 68, by means of a pivotal connection 78^a. The support 78 is provided with an ear or projection 79 and an adjusting bolt or screw 80 is pivotally connected to the member 77 and passes loosely

through the projection 79. A jam nut or collar 81 is provided on the bolt 80 which rests against the ear or projection 79 so that by rotating the jam nut upon the bolt 80 the pivotally-supported member 77 will be moved about its pivot in one direction to tighten the endless chain. The endless upright cutter thus formed is adapted to be moved about its point of pivotal support 72 so as to raise or lower the forward end of the cutter in any suitable manner but preferably in a manner which will now be described.

The support 78 is held in position by means of a projection 82 which extends into a slot 83 in an arm 84 which arm is loosely mounted upon the shaft 72. The slot 83 in the arm 84 is of a length somewhat greater than the length of the projection 82 and an adjusting bolt or screw 85 is provided which projects through the end of the arm 84 and engages the projection 82 so that when the screw 85 is adjusted in one direction, the projection 82 will be moved in the slot 83 to tighten the endless member 64, and when rotated in the opposite direction it will be moved away from the projection 82 to permit the latter to be moved in the slot 83 to loosen the endless member 64. As has been before stated this upright cutter is adapted to be moved about its point of pivotal support 72 by rotating the arm 84 about the shaft 72 to raise and lower the forward end of the cutter, and in order to secure the cutter at any point of its adjustment, there is provided an arm 86 which is connected with the arm 84 and this arm 86 is provided with a substantially upright slot 87 through which slot a pin or fastening bolt 88 projects, and this pin or fastening bolt is supported by a fixed arm 89 (see also Fig. 6). It will be manifest that by loosening the fastening bolt 88, the arm 86 may be raised or lowered and with it the arm 84, which in turn will raise and lower the forward end of the support 78 to the desired extent. When the proper adjustment has been obtained, these parts may be secured in their adjusted positions by tightening the bolt 88.

In order to hold the machine in position and against lateral displacement, an arm 90 (see Fig. 1) is provided on the main supporting frame, which arm is spaced from the side of the machine opposite to that on which the cutters 65 are arranged and terminates adjacent the face 54 of the wall. An adjustable screw 91 may be provided on the arm 90 for engaging the face of the wall. It will thus be seen that both of the cutters and the conveying mechanism receive their motion from a single source of power mounted upon the machine and this power also serves as a means for advancing the machine in the drift or gallery. The under-

kerf 63 and the upright kerf 66 are simultaneously cut and the machine is so constructed that the source of power and all of the operating mechanism will be encompassed by the endless member supporting 70 the cutters 38 so that none of the operating mechanism will project beyond the sides of the frame thereby permitting the machine to not only be compactly constructed but enabling it to be operated successfully and 75 readily within the constricted space necessary for it to operate.

When the kerfs 63, 66, have been cut in the wall of the coal, the wall may be broken down by breaking pieces therefrom and any 80 suitable tool or pick capable of such operation may be employed. A suitable and efficient tool of this character will now be described.

Pivotedly mounted upon a suitable support 91 (see particularly Figs. 4 and 5) is a tubular frame, 92 having a handle 93 by means of which it may be manually adjusted about its point of pivotal support. A reciprocating tool 94 preferably in the form 85 of a pick is provided, one end of which projects into the tubular frame 92 and this end of the pick is provided with a lateral projection 95 which extends through a slot 96 in the frame adjacent the pivot of the frame. 90 An elastic member 97 is provided which surrounds a portion of the tool beyond the frame 92 so that one end will rest against the end of the frame 92 and the other end against a collar 98 adjustably secured on the 100 tool and by means of which collar the tension of the elastic member 97 may be varied. A shaft 99 has a bearing preferably in the support 91 and a crank arm 100 is secured to the shaft 99. This crank arm 100 is preferably provided with an anti-friction roller 101 which is adapted to engage the projection 95 on the tool 94, which projection extends through the slot 96 in the frame 92. It will thus be manifest that when the shaft 110 99 is rotated, the anti-friction roller 101 on the crank arm 100 will engage the projection 95 on the tool 94 during a portion of the rotation of the crank 100 and will draw the end of the tool 94 into the casing 92, and 115 compress the elastic member 97. When the anti-friction roller 101 passes out of engagement with the projection 95 on the tool 94, the tension created on the elastic member 97 will force the operating end of the 120 tool or pick 94 into engagement with the wall of the coal above the kerf 63 which will break down a portion of the wall, as shown in Fig. 4. The front or operating end of the tool 94 may be adjusted at will by the operator grasping the handle 93 and moving the tool about its point of pivotal support, 125 as will be understood.

Motion is imparted to the shaft 99 from the motor 11 through the medium of a gear 130

102 on the shaft 15 which gear 102 meshes with the gear 103 on the shaft 99. With this improved construction it will be apparent that the entire mechanism protrudes very little outside of the path of the cutting of the tools, thus permitting the track 53 on which the cars 52 run to be close to the face 54 of the wall of the coal and also inside of the props so that the tracks may be moved 10 readily toward the face or wall of the coal as the mining progresses.

In order to withdraw the machine from the drift or gallery, a drum 104 is provided (see Figs. 1 and 2) which drum is rotatably 15 supported by means of an axle 105 journaled in a suitable frame 106 arranged at the rear of the machine and a cable 107 is wound around the drum, the free end of which is adapted to be anchored to a suitable fixed 20 support outside of the machine. This drum 104 is rotated to wind the cable thereon by means of a worm wheel 108 connected with the drum, which worm wheel meshes with a worm gear 109 on a shaft 110 journaled in 25 suitable bearings. A gear 111 is secured to the shaft 110 and this gear in turn meshes with the gear 112 secured to the shaft 72 and for rotation therewith. A clutch having an operating arm or lever 113 may be 30 provided, if desired, for disconnecting the drum 104 from its driving mechanism.

What is claimed as new is—

1. In a mining machine, the combination of means for cutting an incision in the material to be mined to effect its breaking down, and horizontal conveyer flights operating in close proximity to and moving with said cutting means and extending in an opposite direction from the latter to convey the 40 material back from the mine wall as soon as it is broken down.

2. In a mining machine, the combination of a chain cutter for producing a kerf in a mine wall, and conveyer flights extending 45 laterally from said chain cutter inwardly or in a direction opposite to the cutters of said chain cutter, to convey the material away from the mine wall as soon as broken down.

3. In a mining machine comprising an undercutting chain cutter, inwardly extending lateral conveyer flights connected to and movable with said chain cutter, and means for breaking down the material from a mine 55 wall above the undercut into the path of said conveyer flights.

4. In a mining machine, the combination with cutting mechanism for producing a kerf in the material to be mined, and conveying mechanism extending backwardly 60 from the mine wall and mounted on and movable with said cutting mechanism into the kerfs produced to act directly on the material as soon as broken down to convey 65 the same back from the mine wall.

5. In a mining machine, the combination of a continuously operating endless cutter for cutting an incision in the material to be mined, and a plurality of conveyer flights extending backwardly from the mine wall 70 and carried by said cutter and moving into the kerf produced thereby to take the material broken down and move it away from the mine wall.

6. In a mining machine, the combination 75 with an endless flexible member, of cutters carried by said member for cutting an incision in the material to be mined, means for operating said endless flexible member together with the cutters carried thereby, and 80 conveyer flights extending inwardly from said flexible member for positively moving the material that falls from above into the path of movement thereof.

7. In a mining machine, the combination 85 with an under-cutting cutter, of conveyer flights connected thereto and extending back therefrom, means for breaking down the material above the under-cut into the path of movement of said conveyer flights, and 90 apparatus for taking the broken down material from said conveyer flights into position for loading.

8. In a mining machine, the combination 95 with an under-cutting cutter, conveyer flights thereon but extending away therefrom, a supplemental conveyer and mechanism for moving the material from said conveyer flights onto said supplemental conveyer.

9. In a mining machine, the combination 100 with an endless flexible member, of cutters carried thereby for cutting the material to be mined, means for operating said member, a platform associated with a part of said 105 flexible member, and conveying means connected to said flexible member and sliding over said platform during the operation of said cutters.

10. In a mining machine, the combination 110 with an endless chain cutter, of a platform adjacent a portion of the path of travel of said endless chain cutter, and a plurality of lateral extensions from said endless chain cutter sliding over said platform to assist 115 said chain cutter in conveying the broken down material away from the place of cutting.

11. In a mining machine, the combination 120 with a kerf-cutting chain cutter, a platform encompassed by said chain cutter, and a plurality of conveyer flights extending from said chain cutter at intervals in position to slide over said platform during a portion of their travel.

12. In a mining machine, the combination 125 with an endless chain cutter, of a frame encompassed by said chain cutter and having a platform at its forward portion, and a plurality of plates extending inwardly at 130

intervals from said chain cutter in position to slide over said platform to assist in conveying away from the mine wall the material broken down therefrom.

5 13. In a mining machine, the combination of means for making a kerf in the material to be mined, means for breaking down the material, said kerf cutting means also operating directly upon the broken down material to convey it away as it is mined, and 10 arms connected to said cutting means to assist in the conveying operation.

14. In a mining machine, the combination with a kerf-cutting chain cutter, of a frame 15 for supporting said chain cutter, means for operating said chain cutter, and conveyer flights extending inwardly from said chain cutter at intervals and sliding over the upper surface of said frame.

20 15. In a mining machine, the combination with an under-cutting chain cutter, of supporting means therefor, adapted to enter a kerf in a mine wall therewith, conveyer flights connected to said chain cutter and 25 movable therewith over said support, and means for breaking down the material above the under-cut produced by said chain cutter, onto said support and in position to be conveyed away from the mine wall by said 30 chain cutter and said conveyer flights.

16. In a mining machine, the combination with cutting mechanism, of means for breaking down material from the mine wall above said cutting mechanism, conveyer flights extending oppositely to said cutting mechanism and moving therewith for removing the broken down material from the mine wall, and apparatus for loading the material removed from the mine wall.

40 17. In a mining machine, the combination with cutting mechanism, of means for breaking down the material adjacent said cutting mechanism, a conveyer connected to and moving with said cutting mechanism for 45 moving back from the mine wall the broken down material, mechanism for feeding forward said cutting mechanism and breaking down means, and means for loading the material conveyed back from the mine wall.

50 18. In a mining machine, the combination of an endless cutting apparatus for cutting the material to be mined, a support for the cutting apparatus, and means for breaking down the material, said support serving as a 55 platform for receiving the material as it is broken down, and said cutting apparatus also operating to engage the broken down material on the platform and to directly convey it away from the point at which it is mined, and arms connected to said cutting means to assist in the conveying operation.

19. In a mining machine, the combination of an endless cutting apparatus for cutting the material to be mined, means for breaking down the material, and a support for the

cutting apparatus embodying means for supporting the latter from its lower face, said support also serving as a platform for receiving the broken down pieces, the upper face of the said cutting apparatus being exposed and said exposed portion operating upon the broken down material to convey it away directly as it is mined, and arms connected to said cutting means to assist in the conveying operation. 70

75 20. In a mining machine, the combination of an endless cutting apparatus for cutting the material to be mined, means for breaking down the material, and a support for supporting the cutting apparatus embodying means for supporting the latter from its lower face, said support also serving as a platform for receiving the broken down pieces, the upper face of the said cutting apparatus being exposed and said exposed portion operating 80 upon the broken down material to convey it away directly as it is mined, a portion of the cutting apparatus operating in a plane above the plane of operation of the other portion thereof, and arms carried by said 85 cutting apparatus and extending over said platform.

21. In a mining machine, the combination of an endless cutting apparatus for cutting a substantially horizontal kerf in the material to be mined, means for breaking down the material above the kerf, means for supporting the cutting apparatus, said supporting means also operating as a platform to receive the material as it is broken 95 down, and conveyer flights connected to said cutting apparatus and projecting laterally over said platform to assist said cutting mechanism in conveying back from the mine wall the material directly after it is mined. 100

105 22. In a mining machine, the combination of an endless cutting apparatus for cutting a substantially horizontal kerf in the material to be mined, means for breaking down the material above the kerf, means for supporting the cutting apparatus, said supporting means also operating as a platform to receive the material as it is broken down, and arms connected with the cutting apparatus and projecting over the platform for 110 conveying away the material directly as it is mined. 115

120 23. In a mining machine, the combination of a combined cutting apparatus and conveyer moving with said cutting apparatus for cutting the material to be mined and conveying it back from the mine wall, loading apparatus, and means for automatically moving the material onto said loading apparatus. 125

130 24. In a mining machine, the combination of a combined cutting apparatus and conveyer moving with said cutting apparatus for cutting the material to be mined and conveying it back from the mine wall,

- a loading conveyer, a frame having guide-ways for said combined cutting apparatus and conveyer to elevate the rear portion of the travel thereof over the rear end of said 5 loading conveyer, and means for moving the material from the first-named conveyer onto said loading conveyer.
25. In a mining machine, the combination with a combined cutting apparatus 10 and conveyer movable with said cutting apparatus, of a frame, a loading conveyer pivoted to said frame, and means for moving the material from said first-named conveyer onto said loading conveyer.
- 15 26. In a mining machine, the combination with means for dislodging material 15 from a mine wall in blocks, a conveyer for moving the material away from the mine wall, loading apparatus and automatic 20 mechanism for pushing the blocks of material horizontally from said conveyer onto said loading apparatus.
27. In a mining machine, the combination with a kerf-cutter, conveyer flights connected thereto, loading apparatus, and means for automatically moving the material from said conveyer flights onto said 25 loading apparatus.
28. In a mining machine, the combination 30 with an under-cutting chain cutter, of conveyer flights connected thereto, a supplemental conveyer, a division plate for said supplemental conveyer, and means for automatically moving the material out of the 35 path of said chain cutter flights onto said supplemental conveyer.
29. In a mining machine, the combination 40 with a combined cutting apparatus and conveyer, of a loading conveyer, means for operating said combined cutting apparatus and conveyer and said loading conveyer, comprising sprocket wheels concentrically mounted, and a frame provided with a guiding pathway for said combined cutting apparatus and conveyer to elevate the same to clear said loading conveyer.
30. In a mining machine, the combination 45 with a combined kerf-cutter and conveyer, a supplemental conveyer, means for effecting the removal of material from said first-named conveyer onto said supplemental conveyer, and means common to both of said conveyers for operating the same.
31. In a mining machine, the combination 50 with a kerf-cutter, of a conveyer connected to said kerf-cutter and moving therewith for taking the broken down material to a predetermined position, a supplemental conveyer for loading the material into mine 55 cars, and an additional conveyer for moving the material from the first-named conveyer onto said supplemental conveyer.
32. In a mining machine, the combination 60 with means for dislodging material from a mine wall in blocks, of a conveyer for moving the blocks of material away from the mine wall, a loading conveyer, an endless chain, flights extending from said endless chain in position to engage the blocks of material and move the same from said first-named conveyer onto said loading conveyer, and means for operating said dislodging means and said conveyers.
33. In a mining machine, the combination 65 with an endless cutter for cutting the material to be mined, of devices extending inwardly and mounted on and moving with said endless cutter and co-operating therewith to form a conveyer for conveying away the material directly as it is mined, and operating mechanism therefor encompassed by said endless cutter.
34. In a mining machine, the combination 70 of horizontal cutting mechanism for the material to be mined, said mechanism embodying an endless flexible member with arms projecting laterally therefrom and conveying means connected therewith; cutters detachably connected therewith, a supporting frame and driving mechanism for 75 the cutting mechanism mounted on the frame and encompassed by the flexible member.
35. In a mining machine, the combination 80 of mechanism for cutting a substantially horizontal kerf in the material to be mined, means for breaking down the material, a supporting frame, and means entirely encompassed by the said cutting mechanism and mounted on the frame for imparting motion to the parts.
36. In a mining machine, the combination 85 of a combined endless cutter and conveyer for cutting the material to be mined and for conveying away the material which has been mined outside of the cut and directly as it is mined, a support for the cutter and conveyer, said support receiving the material to be conveyed away as it is mined, 90 arms on said conveyer extending over said support and a motor encompassed by the cutter and conveyer for operating the same.
37. In a mining machine, the combination 95 with a chain cutter, of mechanism for operating the same, a frame, and a track in said frame for confining the movement of said chain cutter to a predetermined path to bring the same into a predetermined position at the mine wall when at the forward portion of the frame, and to elevate said chain cutter to a different plane for facilitating repair or renewal when at the rear portion of said frame.
38. In a mining machine, the combination 100 with a frame, of a chain cutter, and a track 105 guideway in said frame for said chain cutter, said guideway having its transverse portions at the front and rear of the frame in different planes, and its longitudinal portions on inclines.

39. In a mining machine, the combination with a chain cutter, of a frame, and a guideway in said frame for said chain cutter to elevate the path of travel of the latter into a different plane after the same emerges from its cutting position.
40. In a mining machine, the combination with a kerf-cutter, of a pick machine for breaking down material from a mine wall above the cut produced by said kerf-cutter, flights connected to said kerf-cutter for conveying broken down material to a predetermined position, a loading conveyer, and an endless flight conveyer for moving the material from said predetermined position onto said loading conveyer.
41. In a mining machine, the combination of a combined cutter and conveyer for cutting a substantially horizontal kerf in the material to be mined and for conveying away the mined material directly as it is mined, a motor encompassed by the cutter and conveyer for operating the same, a second cutter operating to cut a kerf transversely with respect to the first said kerf, means for adjusting the second cutter in an upright plane, means for maintaining it in its adjusted position, means operatively connecting the second said cutter with the motor for operation thereby.
42. In a mining machine, the combination of a combined cutter and conveyer for cutting a substantially horizontal kerf in the material to be mined and for conveying away the mined material directly as it is mined, a motor encompassed by the cutter and conveyer for operating the same, a second cutter operating to cut a kerf transversely with respect to the first said kerf, means for supporting the second said cutter for adjustment about a horizontal pivot, means for maintaining the cutter in its adjusted position, and means operatively connecting the second said cutter with the motor for operation thereby.
43. In a mining machine, the combination of an endless cutter for cutting a substantially horizontal kerf in the material to be mined, a motor encompassed thereby for operating the cutter, means for cutting an upright kerf in the material, means operatively connecting the last said means with the motor for operation thereby, means operating above the horizontal kerf for breaking down the material, and means operatively connecting the breaking down means with the motor.
44. In a mining machine, the combination of an endless cutter for cutting a substantially horizontal kerf in the material to be mined, a motor encompassed thereby for operating the cutter, means for cutting an upright kerf in the material, means operatively connecting the last said means with the motor for operation thereby, means op-
- erating above the horizontal kerf for breaking down the material, means operatively connecting the breaking down means with the motor, means for advancing the machine in the mine, and means also operatively connecting the last said means with the motor.
45. In a mining machine, the combination of an endless cutter for cutting a substantially horizontal kerf in the material to be mined, a motor encompassed thereby for operating the cutter, means for cutting an upright kerf in the material, means operatively connecting the last said means with the motor for operation thereby, means operating above the horizontal kerf for breaking down the material, means operatively connecting the breaking down means with the motor, means for withdrawing the machine from the work, and means operatively connecting the last recited means with the motor for operation thereby.
46. In a mining machine, the combination with a kerf-cutter, of a frame, and guideways in said frame for said kerf-cutter to elevate the kerf-cutter during the rear portion of its path of travel out of the plane of the forward path of travel of said kerf-cutter.
47. In a mining machine, the combination with a kerf-cutting chain cutter, of conveyer flights connected thereto, a frame having guideways for said chain cutter to elevate the latter out of the plane of its forward path of travel, a loading conveyer extending under said chain cutter, and means for moving the material from said conveyer flights onto said loading conveyer.
48. In a mining machine, the combination with a frame, having its lower surface in a substantially horizontal plane and its upper forward surface at the front and rear in substantially horizontal planes at different elevations with the intermediate spaces at the sides on inclines, of a chain cutter for cutting a kerf at the base of a mine wall, and a guideway for said chain cutter to direct the same over a path of travel adjacent said horizontal surfaces and at the sides of said inclines.
49. In a mining machine, the combination with an under-cutting chain cutter, of a frame having guideways for said chain cutter to elevate the latter during its path of travel over the rear portion of said frame out of the plane of the path of travel over the forward portion of said frame, means comprising a sprocket wheel for driving said chain cutter, a loading conveyer comprising a sprocket wheel connected to the shaft of the first-named sprocket wheel for operation thereby, conveyer flights connected to said chain cutter, and means for moving the material from said conveyer flights onto said loading conveyer.
50. In a mining machine, the combination

with an under cutter, of a side cutter, a pick machine for breaking down material from a mine wall above said under cutter, conveyer flights connected to said under cutter, 6 a swinging loading conveyer, and means for automatically moving the material from said under cutter flights onto said loading conveyer.

51. In a mining machine, the combination 10 with a side kerf-cutter, of an under-cutting kerf cutter, a frame, means extending forwardly from said frame to engage the face of the mine wall and guide the forward path of travel of said side cutter, means for operating said kerf-cutters, mechanism for feeding forward said frame during the operation of said kerf-cutter, a pick machine

for breaking down the material above the under-kerf, conveyer flights connected to the under-cutting kerf-cutter, a loading conveyer pivotally mounted on said frame, guideways for elevating said under-cutting kerf-cutter at its rear portion of travel above said loading conveyer, and means for moving the material from said conveyer 25 flights onto said loading conveyer.

In testimony whereof I have signed my name to this specification, in the presence of two subscribing witnesses, on this 29th day of October, A. D. 1910.

EDMUND C. MORGAN.
